UNITED STATES PATENT OFFICE.

GEORGE FRANKLIN TRIPP, OF FLINT, MICHIGAN.

FIREPLACE.

1,087,852.

Specification of Letters Patent. Patented Feb. 17, 1914.

Application filed May 10, 1913. Serial No. 766,767.

To all whom it may concern:

Be it known that I, GEORGE F. TRIPP, a citizen of the United States, residing at Flint, in the county of Genesee and State of Michigan, have invented new and useful Improvements in Fireplaces, of which the following is a specification.

The invention has relation to a fire place having a contracted throat for the escape 10 of smoke into the flue or chimney, a pan being located in the throat and serving both as a wind check and a receptacle to receive soot, and consists in the peculiar formation of the fire place and in the means for 15 strengthening the same and forming a support for the combined wind check and soot pan.

The invention consists of the novel features, details of construction and combination of parts, which hereinafter will be more particularly set forth, illustrated in the accompanying drawings, and pointed out in the appended claims.

Referring to the drawings, forming a 25 part of the specification, Figure 1 is a section of a fire place embodying the invention. Fig. 2 is a vertical section on the line $\alpha-\alpha$ of Fig. 1. Fig. 3 is a detail view, of the bar which closes the open side of the angle cross 30 bar forming a stay for the upper end of the fire place back. Fig. 4 is a detail view of the pan.

Corresponding and like parts are referred to in the following description, and indicated in all the views of the drawings, by the same reference characters.

The jambs of the fire place are indicated by the numeral 1 and flare at their upper ends. The back 2 of the fire place curves 40 forwardly at its upper end, which is strengthened and stayed by means of a cross bar 3, which preferably consists of an angle iron arranged with the space formed between the wings facing upward and closed 45 by means of a bar 4 which is arranged in a horizontal plane. The top of the first place is indicated by the numeral 5 and is approximately of arch form and inclines upwardly and rearwardly as shown most 50 clearly in Fig. 2, said upwardly and rearwardly inclined portion being indicated at 6. The flue 7 is located directly above the spring of the back 2 and at some distance from the face of the fire place or chimney 55 breast. The flue or chimney 7 is lined. An angle bar 8 supports the facing of the chim-

ney or flue and an angle bar 9 supports the brick or tile forming the wall adjacent the front of the flue or chimney. The space between the facing and the inner wall is 60 filled preferably with concrete. The flue or chimney 7 is contracted at the top of the back 2.

A pan 10 is located in the plane of the throat of the fire place and may be of any 65 construction and preferably consists of a cast metal front and a sheet metal back, bottom and sides. For convenience of manipulation the pan 10 is provided near each end with handles 11. A baffle 12 extends 70 upwardly and rearwardly from the front of the pan 10 and serves as an extension of the inner wall of the throat and also acts as a check to prevent down draft and soot from being carried into the room in which the 75 fire place is located.

To retain the pan in proper position openings 13 are formed in its bottom and receive studs 14 extending upwardly from the member 4 of the cross bar. The pan catches 80 any soot that may fall in the flue or chimney and by removing such pan from time to time the accumulation of soot, ashes and the like may be dumped in any convenient place. As shown most clearly in Fig. 2 the 85 pan occupies a position in line with the flue or chimney 7 and extends slightly into the throat, hence any soot falling in the flue is received and retained in the pan. Moreover, down draft strikes the rear portion 90 of the pan and is deflected by such pan and the baffle 12 and is caused to ascend in the front portion of the flue together with the warm air or smoke and gases passing off through the flue. 95

From the foregoing description, taken in connection with the accompanying drawings, the advantages of the construction and of the method of operation will be readily apparent to those skilled in the art 100 to which the invention appertains, and while I have described the principle of operation of the invention, together with the device which I now consider to be the best embodiment thereof, I desire to have it understood 105 that the device shown is merely illustrative, and that such changes may be made when desired as are within the scope of the claims appended hereto.

Having thus described the invention what 110 is claimed as new, is:—

1. A fire place having a contracted throat

and having the upper portion of its back extended forwardly to overhang the fire place, a cross bar engaging and sustaining the upper portion of the back and supported at its ends in the jambs of the fire place, a pan located in the plane of the throat with its front portion extending therein a short distance and adapted to rest upon the said cross bar, a baffle inclining upwardly and rearwardly from the front of the pan, and retaining means between the pan and the said cross bar to retain the said pan in the proper position.

2. A fire place having the upper portions of its jambs flared and having the upper portion of its back extending forwardly to overhang the fireplace, a contracted throat being formed between the upper portion of the fire place and the flue, a cross bar engaging the upper end of the back and forming a stay therefor and having its ends let into the jambs, a pan located in the plane of the contracted throat with its front portion extending slightly therein and resting upon the said cross bar, a baffle inclining upwardly and rearwardly from the front

of the pan, and retaining means between the pan and cross bar.

3. A fire place having the upper portions of its jambs flared and the upper portion of its back extended forwardly, said fire place having the flue directly above the overhanging portion of the fire place back, the throat between the fire place and flue being contracted, a cross bar engaging the upper end of the back and supported at its ends in the fire place jambs, angle irons supporting the facing and the wall adjacent the front of the flue, filling between such facing and wall and having its lower part upwardly and rearwardly inclined, a pan supported upon the cross bar engaging the upper end of the fire place back, a baffle inclining upwardly and rearwardly from the front of the back, and retaining means between the pan and cross bar.

In testimony whereof I affix my signature in presence of two witnesses.

GEORGE FRANKLIN TRIPP.
